CLAIM

The ornamental design for a simulative water toy, substantially as shown and described.

DESCRIPTION

FIG. 1 is a top plan view of a simulative water toy showing my new design;

FIG. 2 is a side elevational view thereof;

FIG. 3 is a side elevational view thereof of the side opposite that shown in FIG. 2;

FIG. 4 is a bottom plan view thereof;

FIG. 5 is a front elevational view thereof; and

FIG. 6 is a rear elevational view thereof.
